DESIGN FOR A BOTTLE

Lurelle V. Guild, New York, N. Y., assignor to Maryland Distillery Inc., Relay, Md., a corporation of Maryland

Application February 7, 1935, Serial No. 55,279

Term of patent 14 years

To all whom it may concern:

Be it known that I, Lurelle V. Guild, a citizen of the United States of America, residing at New York city, New York County, New York, have invented a new, original, and ornamental Design for a Bottle, of which the following is a specification, reference being had to the accompanying drawing, forming part thereof.

In the drawing:

ing my new design.

I claim:

The ornamental design for a bottle as shown.
